UNITED STATES PATENT OFFICE.

CHARLES E. SAWYER, OF BOSTON, MASSACHUSETTS.

PLATEN PRINTING-MACHINE.

SPECIFICATION forming part of Letters Patent No. 510,146, dated December 5, 1893.

Application filed June 17, 1893. Serial No. 477,950. (No model.)

To all whom it may concern:

Be it known that I, CHARLES E. SAWYER, a citizen of the United States, residing at Boston, in the county of Suffolk and State of Massachusetts, have invented certain Improvements in Platen Printing-Machines, of which the following is a full, clear, and exact description, reference being had to the accompanying drawings, making part of this specification, in which—

Figure 1 is a side elevation of a platen printing-machine constructed in accordance with my invention. Fig. 2 is a front elevation of the same. Fig. 3 is a plan view of the same. Fig. 4 is an enlarged side elevation of a portion of the machine. Fig. 5 is a plan of the same. Fig. 6 is a sectional diagram showing the position of the parts when the form-carriers are at the end of their outward traverse. Fig. 7 is a similar diagram showing the form-carriers at the end of their inward traverse in a position for printing. Fig. 8 is a detail of the platen showing the upper half or portion lowered or "thrown off" to avoid taking an impression. Fig. 9 is a detail in perspective of one of the "throw off" rock-shafts by means of which the upper portion of the platen is raised and lowered. Fig. 10 is a perspective view of the upper half or portion of the platen, showing the tympan-frame made in two parts, each pivoted to the removable top plate of the platen. Fig. 11 is a perspective view of one of the form-roller hangers. Figs. 12 and 13 are details to be referred to.

My invention relates to bed and platen printing machines, more particularly those designed for printing tags, tickets, labels, and other small articles; and my invention has for its object to provide a machine of this character in which very short movements of the reciprocating parts are required, thereby enabling the machine to be run at a greater speed, while at the same time the friction and wear of the parts are reduced to a minimum.

To this end my invention consists in certain novel features, combinations of parts, and details of construction as hereinafter set forth and specifically pointed out in the claims.

In the said drawings, A represents the framework of the machine and B the bed-plate, upon which is placed the stationary platen C which

is secured in place thereon by a central clamping screw *a*, Figs. 2 and 6, and is made adjustable in height by means of four leveling screws *b* on which it rests, said screws being located 55 at the corners of the platen and passing down through the bed-plate as shown in Figs. 2 and 6, beneath which they are provided with hand-wheels *c* by which they be turned to effect the desired adjustment of the platen.

D represents the vertically reciprocating form-bed which co-operates with the platen C, said bed being provided on its upper side with a hollow actuating plunger *d* adapted to slide in a suitable guide E bolted to the side pieces of the framework A, said plunger having pivoted to it at 25 a rod *e* connected to the strap of an eccentric G on the main or driving shaft H by means of which the desired vertical reciprocating movement is imparted to the form-bed D. The driving shaft H is supported in bearings in the upper side-pieces of the framework, and carries at one end the fast and loose pulleys 26, 27, and at the opposite end a bevel gear *g*, which meshes 75 with a smaller bevel gear *g*², on a shaft *h*, Fig. 3, having its bearings in brackets on the framework and carrying at one end a crank-disk I having an adjustable crank-pin *i* to which is pivoted a rod *k*, the lower end of which is connected with a ratchet and pawl mechanism J adapted to intermittently rotate the lower one of a pair of feed-rolls *l*, *m*, between which passes the web of paper 28 which is drawn in a well known manner from a roll, 85 not shown. The upper feed-roll *l* is forced downward toward the lower roll *m*, by means of suitable springs 29, Fig. 2, which exert a pressure upon the vertically sliding journal boxes of said roll, whereby the necessary friction upon the paper is produced to insure a positive feed.

The form-bed D extends out beyond the platen at the front and rear, as shown in Figs. 1, 4, 5, 6, and 7, and is provided with horizontal grooves or guideways 30, in which are fitted two reciprocating type-form carriers L, L, which are arranged to slide horizontally in said ways in opposite directions away from and toward the center of the form-bed D, 95 100 whereby the type-forms 31, secured to the carriers L in any suitable manner, are caused

to pass over and in contact with the form-inking rollers both on their outward and inward movement or traverse.

Each of the type-forms is inked by a series 5 of form-inking rollers *w*, the shafts of which are supported in hangers *p* adjustably secured to the sides of the form-bed *D* by means of slots and bolts 70, 71, and adjusting screws 72; said hangers being provided on the inner 10 side with bosses 73 having vertical slots 32, shown in Figs. 6 and 11, for the reception of the journals of the form-roller shafts, whereby as the form-bed descends to give the impression, the journals of the form-rollers rise 15 in the slots 32, and the form-rollers are thus permitted to settle or adjust themselves around the curved or convex surface of the ink cylinder *M* to insure the proper supply of ink therefrom before the next outward movement 20 of the type-forms, while on the ascent of the form-bed the form-rollers descend by their own gravity as far as permitted by the slots 32, which causes the tops of said rollers to be brought to a uniform level, thus insuring 25 perfect and complete contact of the form-rollers with all parts of the type-forms as the latter pass thereover, both on their outward and inward movement.

The type-form carriers *L*, *L*, are reciprocated in their guideways 30 to bring them alternately into their printing and inking positions by means of rods *q*, *q*, pivoted thereto at 33, and having their outer ends pivoted at 34 to levers *N* depending from long hubs or 35 sleeves 20 secured to horizontal rock-shafts *P* which are supported in bearings in the framework and arranged on opposite sides of the machine, said hubs or sleeves 20 being each provided with an inwardly curved arm 40 *Q* carrying at its upper end an anti-friction roll 35 which rests on the surface of an actuating cam *R* on the main or driving shaft *H*. The rolls 35 are kept constantly in contact with the cams *R* by means of stiff spiral 45 springs 36, the opposite ends of which are attached to arms 37 extending upward from the hubs 20 on the rock-shafts *P*, whereby as the shaft *H* is rotated, the cams *R* acting on the rolls 35 of the arms *Q* lift the same against 50 the stress of the springs 36, and through the connections described, cause the type-form-carriers *L* to be simultaneously moved inward to their printing positions as shown in Figs. 1 and 7, the outward movement of the carriers 55 *L* with their type-forms to enable the latter to receive their supply of ink as described, being effected by the springs 36 as the cams revolve. The arrangement of the mechanism is such that as soon as the plunger *d* with the 60 form-bed *D* has risen about one-eighth of an inch after producing the impression, the type-forms commence to move outward to be inked and are returned to their printing positions by the time the eccentric *G* has completed its 65 revolution, and by attaching the form-rollers to the reciprocating form-bed as described, so that they will move up and down therewith

and thereby be caused to periodically come into contact with the ink-cylinders *M*, arranged directly beneath them in stationary 70 bearings, I am enabled to ink the type-forms and feed the paper while the form-bed is in motion, very short movements of the reciprocating mechanism being consequently required under this construction, which renders 75 it possible to run the machine at a greater speed with a minimum of friction and wear, advantages not possessed in ordinary bed and plateu printing machines.

The shafts of the ink-cylinders *M* by which 80 the form-rollers are supplied with ink are supported in stationary bearings *t* in the framework, and are each provided with a grooved pulley 38 which is driven by a belt 39 from a grooved pulley 40, on a shaft 41 85 having its bearings in the lower portion of the framework and carrying at one end a pulley 42 which is driven by a belt 43 from a pulley 44 on the driving shaft *H*, as shown in Fig. 2.

The ink-cylinders *M* are supplied with ink by distributer-rolls *w'* and vibrator rolls 45 of the usual construction which are supplied by ductor-rolls 46 which are adapted to be brought into contact with the fountain-rolls 95 47 in the ink-fountains 48 at each descent of the form-bed *D* in the following manner: The shaft of each of the ductor-rolls 46 is supported in bearings at the outer end of a frame 49 pivoted to lugs on the ink-fountain, said frame being pressed upward by flat springs 52 which serve to lift the ductor-roll 46 away from the fountain-roll 47 and keep it in contact with the vibrator-roll 45, as shown in Fig. 4, until the form-bed begins to descend, 105 which causes two downwardly-extending arms or bars 53 attached thereto, one on each side, to come into contact with and depress the frame 49 and thereby bring the ductor-roll 46 into contact with the fountain-roll 47, 110 which latter is rotated on the ascent of the form-bed by a ratchet and pawl mechanism 50 operated by a lever 54 connected by a rod 55 with the vertically reciprocating form-bed *D*; and in this manner a fresh supply of ink 115 is transferred from the fountain-roll to the ductor-roll at each descent of the form-bed. The amount of ink taken up by the fountain-roll is regulated by an inclined plate 56 shown dotted in Figs. 1 and 4, made adjustable by a 120 series of screws 57, this latter device being well known and forming no part of my invention. The "throw off" device by means of which the working surface of the platen is lowered or "thrown off" to prevent the taking of an impression will now be described. The platen *C* is composed of two principal portions or halves *a'*, *b'*, the upper portion or half *a'* having a false or removable plate 58 which forms the upper or working face of the 125 platen, and to which is secured the tympan-frame 59 by which the blanket 21 and tympan-sheet 22, Fig. 7, are held in place upon the platen in the usual manner. The remov-

able top-plate 58 is steadied and held in place by pins 23, (shown in Figs. 8 and 10) projecting from the portion a' into holes in the under side of the plate 58 which permit of the latter being easily removed with the tympan-frame whenever it may be found necessary to gain access to the tympan-sheet or blanket to adjust the same, thereby avoiding the necessity of removing the entire portion a' , which would be inconvenient. The upper surface of the lower portion b' of the platen is provided with a series of half-round grooves 60 which form sockets or bearings for a corresponding number of rock-shafts d' , each of which is provided with a longitudinal rib or projection 61, Figs. 6, 7, 8, and 9, which fits into a rectangular groove 62 formed in the under side of the upper portion a' of the platen, the height of these projections 61 being such that when turned up by rocking the shafts d' a quarter revolution into the position shown in Figs. 4, 6, and 7, they will act upon the portion a' and raise it clear of the portion b' to its proper printing level, the corners of the projections 61 being rounded off as shown to facilitate this movement. When however it is desired to "throw off" the platen so as not to print as the web passes beneath the type-forms, the projections 61 are turned down flatwise as shown in Fig. 8, when they will lie snugly within the grooves 62, this movement causing the portion a' to descend and rest upon the surface of the portion b' , in which position the working or top surface of the platen will be below its printing level and no impression will be taken on the descent of the form-bed D.

The rock-shafts d' are each provided at one end with a slotted crank e' , Figs. 1 and 9, with which engages a pin f' on a horizontal slide bar g' moving in a groove 75 in the portion b' , as shown in Fig. 13, said bar g' being actuated by a slotted lever W projecting from a stud i' , to which is secured a long lever k' provided with a handle 63 at each end, whereby it may be operated from each side of the machine to simultaneously oscillate the rock-shafts d' and thus raise or lower the working surface of the platen as may be required; suitable guides 64 secured to the portion a' and fitting snugly against the front and rear sides of the portion b' and sliding in ways attached thereto, as shown in Figs. 10 and 12, being employed to keep the portion a' in position while being raised or lowered as described.

What I claim as my invention, and desire to secure by Letters Patent, is—

1. In a platen printing-machine, the combination of a vertically reciprocating form-bed provided with guideways, form-rollers mounted in hangers or supports secured to said form-bed, a type-form-carrier having a horizontally reciprocating movement in said guideways, whereby the type-form is brought into contact with the form-rollers, a platen with which said form-bed co-operates, and

means, substantially as described, for vertically reciprocating the form-bed and horizontally reciprocating the type-form-carrier 70 in the ways thereof to bring the type-form into contact with the form-rollers and return it to its printing position during the time that the form-bed is in motion, substantially as set forth.

2. In a platen printing-machine, the combination, with a platen and a vertically reciprocating form-bed co-operating therewith, said form-bed being provided with horizontal guideways, of a type-form-carrier having a horizontally reciprocating movement in said guideways, and a series of horizontally arranged form-rollers supported in vertically slotted hangers attached to said form-bed and adapted to receive ink from an ink-cylinder 85 arranged directly beneath the same, whereby said form rollers are permitted to rise and adapt themselves to the curved surface of the ink-cylinder on the descent of the form-bed and drop to a uniform level on the ascent 90 of said form-bed to permit the type-form to be brought into contact with all of said form-rollers as it passes thereover, substantially as described.

3. In a platen printing-machine, the combination, with a vertically reciprocating form-bed provided with guideways extending outward from its center in opposite directions, of two type-form-carriers having a horizontal movement in said guideways simultaneously 100 away from and toward the center of the bed, whereby the type-forms are caused to be inked, a series of form-rollers for each type-form mounted in hangers or supports secured to and moving with the form-bed, a platen with 105 which said form-bed co-operates, and means, substantially as described for vertically reciprocating the form-bed and horizontally reciprocating the type-form-carriers in their guideways simultaneously in opposite directions to ink the type-forms and return the same to their printing positions while the form-bed is in motion, substantially as set forth.

4. In a platen printing-machine, the combination, with a vertically reciprocating form-bed provided with guideways extending outward from its center in opposite directions, of two type-form-carriers having a horizontal movement in said guideways simultaneously 120 away from and toward the center of the bed, whereby the type-forms are caused to be inked, a series of form-rollers for each type-form mounted in hangers or supports secured to and moving with the form-bed, a platen 125 with which said form-bed co-operates, the levers N , connected with said type-form-carriers by rods q , the horizontal rock-shafts P provided with arms Q and 37, and the cams R and springs 36 for actuating the type-form-carriers in opposite directions, all operating substantially as described.

5. In a platen printing-machine, the combination of the vertically reciprocating form-

bed D, its plunger d and the eccentric G for actuating the same, said form-bed being provided with guideways 30 extending outward from its center in opposite directions, the two 5 type-form-carriers having a horizontal movement in the guideways 30 simultaneously away from and toward each other, the platen C, a series of form-rollers for each type-form, said rollers having their journals supported in 10 vertical slots 32 in hangers p secured to the form-bed, two ink cylinders M, arranged one beneath each series of form-rollers, the rock-shafts P, levers N, connected by the rods q, with the type-form carriers the arms Q and 15 37, the actuating cams R, and the springs 36, all operating substantially as set forth.

6. In a platen printing-machine, a platen composed of two portions vertically separable from each other, combined with rock-shafts 20 interposed between said portions and provided with projections adapted to act upon the upper portion of the platen to raise or lower the working surface of the same, a hand-lever connected with said rock-shafts for actuating the same, and guides for keeping the upper portion of the platen in place, substantially as set forth.

7. In a platen printing-machine, the platen C composed of a lower portion b' and an upper portion a' separable vertically from each other, and provided with suitable guides, said portion a' having grooves 62 on its under side, in combination with the rock-shafts d' hav-

ing their bearings in the lower portion b' and provided with ribs or projections 61 fitting 35 within said grooves 62, and adapted when moved into a vertical position to raise the upper portion of the platen and hold the same in its printing position, and when turned into a horizontal position to lower or "throw 40 off" the platen to prevent the taking of an impression, and means substantially as described for oscillating the rock-shafts to raise and depress the working surface of the platen, substantially as set forth. 45

8. In a platen printing-machine, the combination, with the vertically reciprocating form-bed and its horizontally reciprocating type-form-carrier, of the fountain and fountain-roll, the latter rotated intermittently by 50 ratchet and pawl mechanism connected with the form-bed, the ductor-roll mounted on a movable frame and normally held out of contact with the fountain-roll, and a bar or projection on the form-bed adapted to depress 55 the ductor-roll frame on the descent of the form-bed to bring the ductor-roll into contact with the fountain-roll and retain it in such position until the ascent of the form-bed, substantially as and for the purpose set forth. 60

Witness my hand this 9th day of June, A. D. 1893.

CHARLES E. SAWYER.

In presence of—

P. E. TESCHEMACHER,
R. HENRY MARSH.
